His atty.

UNITED STATES PATENT OFFICE.

CHARLES L. GEORGE, OF FINDLAY, OHIO, ASSIGNOR TO THE BUCKEYE TRACTION DITCHER COMPANY, OF FINDLAY, OHIO, A CORPORATION OF OHIO.

INTERNAL PIPE-WRENCH.

1,313,479.

Specification of Letters Patent.

Patented Aug. 19, 1919.

Application filed April 21, 1919. Serial No. 291,606.

To all whom it may concern:

Be it known that I, CHARLES L. GEORGE, a citizen of the United States, and a resident of Findlay, in the county of Hancock and State of Ohio, have invented a certain new and useful Internal Pipe-Wrench; and I do hereby declare the following to be a full, clear, and exact description of the invention, such as will enable others skilled in the art to which it appertains to make and use the same, reference being had to the accompanying drawings and to the characters of reference marked thereon, which form a part of this specification.

This invention relates to wrenches of the internal type for use more particularly in connection with the turning of pipes, such, for instance, as those used in water, gas and oil mains and in which the pipes are in threaded connection with each other, either directly or through the medium of a coupling collar.

The object of my invention is the provision of a simple and improved apparatus of this character which is strong, durable and inexpensive in its construction, efficient in its operation and easy to handle.

The invention is fully described in the following specification and while, in its broader aspect, it is capable of embodiment in numerous forms, a preferred embodiment thereof is illustrated in the accompanying drawings, in which,—

Figure 1 is a front end elevation of an apparatus embodying the invention with a part broken away. Fig. 2 is a central longitudinal section thereof on the line 2—2 in Fig. 1 with parts in full. Fig. 3 is a view similar to Fig. 1 with the front end plate and clutch members assembled, and Fig. 4 is a perspective view of one of the clutch members.

Referring to the drawings, 1 designates the wrench head which has its inner end portion preferably hollow and provided at its outer end with an enlargement 2 which is peripherally recessed to provide a race-way for receiving a carrying collar 3, which is adapted to loosely turn thereon and is provided at opposite sides with handles 4. The head 1 is of suitable size forward from the enlargement 2 to loosely project into a pipe end of a size for which it is adapted, and the forward end portion of the head is

provided with the extension 5, which is preferably, but not necessarily, reduced in diameter relative thereto.

The extension 5 is provided with a plurality of equidistantly spaced peripheral recesses 6, which are open at their outer ends and are circular in cross-section with the outer peripheral sides thereof open, as shown. The outer open side of each recess 6 constitutes less than half of a circle so that a circular member inserted endwise into a recess and substantially fitting the same for loose turning movements therein is prevented from outward radial movements due to the wall of the recess constituting more than half of a circle, as is apparent.

Mounted in each recess 6 is a cylindrical clutch member 7, the diameter of which is substantially that of the recess so as to turn freely therein but not to have undue lateral play. The outer peripheral sides of the clutch members project beyond the peripheral line of the extension 5 and to near the peripheral line of the body portion of the head, and each member is provided on its outer side with a clutch jaw 8 which is set partially into a recess or seat formed in the periphery of the member. This jaw has its outer surface preferably serrated or provided with clutch teeth and is normally disposed at one side of the side opening of the recess in which position its clutch surface projects only slightly beyond the peripheral surface of the body portion of the head 1. It is evident, however, that upon a turning of a clutch member 7 to the left, or toward the center of the side opening of its recess 6, as shown in Fig. 3, the clutch jaw 8 will have an outward camming action so as to effect a tightening thereof against the inner surface of a pipe in which the end of the head is disposed, due to the axis of the clutch member being offset with respect to the axis of the head and pipe in which inserted.

The clutch member 7 is normally held in the released position shown by a coiled spring 9, which is set into a socket 10 provided axially in the outer end of the clutch member, one end of said spring being anchored in the inner end of the socket to resist a turning of the spring within the socket and the other end thereof being projected transversely to the outer end of the clutch member toward the center of the

head and in side thrust engagement with a stud 11 projecting outward axially from the head extension 5. The turning movement of the clutch members 7 from normal or released position is reverse to the intended pipe turning or driving movement of the head so that the frictional coaction of the clutch jaw 8 with the wall of a pipe in which disposed when the head is so turned will cause a movement of the clutch members in the opposite direction to effect an outward projection thereof into firm clutch engagement with the pipe.

A plate 12 is secured to the outer end of the head extension 5 by screws 13 and covers the outer ends of the clutch members 7, thereby retaining them in the sockets 6, and also covers the outer laterally extended ends of the springs 9.

The wrench is adapted for use either as a right or left wrench by merely reversing the clutch member 7 end for end, in the recesses 6, and shifting the springs 9 from one end to the other of the members which are provided with a recess 10 in each end thereof.

The head 1 is provided at opposite sides of its rear end with perforated lugs 14 to which any suitable power means may be attached.

I wish it understood that my invention is not limited to any specific construction, arrangement or form of the parts, but is capable of numerous modifications and changes without departing from the spirit of the claims.

Having thus described my invention, what I claim as new and desire to secure by Letters Patent, is,—

1. A wrench head adapted for projection into a pipe end, said head having a peripheral recess, a clutch member mounted for rocking movements in said recess about an axis which is offset relative to the head axis, said member having a clutch surface which is projected outward into tightening clutch engagement with an encircling pipe when the clutch member is rocked in one direction relative to the head.

2. A wrench head adapted for projection into a pipe end, said head having a peripheral recess, a clutch member mounted for rocking movements in said recess about an axis which is offset relative to the head axis, said member having a clutch surface which is projected outward into tightening clutch engagement with an encircling pipe when the clutch member is rocked in one direction relative to the head, and means acting on the clutch member to normally

retain it in released position relative to the head.

3. In a wrench of the class described, a head adapted for projection into a pipe, said head having a circular recess in its periphery with the recess axis parallel to the head axis and with the side peripheral opening of the recess of less width than the recess diameter, a cylindrical clutch member rotatably mounted in said recess and having a clutch surface projecting without the recess opening and adapted to have inward and outward movements relative to the head axis when the clutch member is rotated in its recess, and means normally retaining the clutch member in one position of its movement in the head recess.

4. In a wrench of the class described, a head adapted for projection into a pipe, a clutch member mounted in a side portion of said head for rotary movements relative thereto about an axis which is parallel to and offset from the head axis, said member having a clutch surface adapted to be projected a greater or less distance without the periphery of the head by a relative turning of the member and head, and said member having an axial socket in an end thereof, a coiled tension spring in said socket having one end fixed to the member to resist a turning of the spring therein and having its other end projected without the member transversely thereof and in side thrust contact with a part of the head to resist a turning of the clutch member from normal position.

5. In a wrench of the class described, a head having an end portion adapted to be projected into a pipe and provided in the outer end thereof with a plurality of circular recesses with their axes parallel to the head axis and with a portion of their outer sides, which is less than one-half of a circle, open peripherally of the head, cylindrical clutch members adapted to be inserted endwise into said recesses and having clutch surfaces projected through the side openings thereof and adapted for relative rocking movements therein by circular movements of the members in the recesses, the clutch surfaces being moved outward relative to the head axis when the members are turned from normal position, means retaining the members in normal position relative to the head, and means secured to the outer end of the head and retaining said members in the head recesses.

In testimony whereof, I have hereunto signed my name to this specification.

CHARLES L. GEORGE.
